CHIME SIGNAL

John G. Jolly, Cincinnati, Ohio, assignor to Nu Tone,
Inc., Cincinnati, Ohio, a corporation of New York

Application November 20, 1956, Serial No. 43,844

Term of patent 14 years

(Cl. D72—1)

Figure 1 is a perspective view of a chime signal showing my new design.

Figure 2 is an enlarged cross sectional view taken on the line 2—2 in Figure 1 illustrating the configuration of the front thereof.

Figure 3 is a fragmentary enlarged cross sectional view taken on the line 3—3 of Figure 1.

The top of the chime signal, not shown, is plain and the other side, not shown, is substantially like the side shown.

I claim:

The ornamental design for a chime signal, substantially as shown and described.
